D12-207. OF D 993 EX

General Designs.

James F. Fox's Carriage Hubs &c
Patented March 9. 1858.

James Fox

James Ives, of Mount Carmel, Conn.
Letters Patent No. 993. Dated March 9th 1858.

The schedule referred to in these Letters Patent and making part of the same.

To all whom it may concern:

Be it known that I, James Ives, formerly of the town of Hamden, now of Mount Carmel in the county of New Haven, and state of Connecticut, have invented a new and original design for carriage hub sand bands, and I do hereby declare that the following is a full, clear and exact description of the same, reference being had to the accompanying drawing forming part of this specification:

The annexed drawing represents the distinguishing feature of my invention which consists in the configuration of the band. The bands in common use are made with straight sides the shanks or teeth by which they are fastened to the hubs of wheels forming a continuous line with the band itself both on its outer and inner surface. I have the band cast with the inner end (by which I mean the end of the band that sets against the hub) flaring or spreading outwards in a circular form by which a concave form is given to the outer surface a, of the band and a concave form to the inner surface b, thus forming the band not interfering with the shanks or teeth c. c. c. projecting

from and forming on their inner side a continuous line with the inner surface of the band before it commences to flare as seen in the drawing. A small bead may be made on the larger end of the band if desired. This form of band is more ornamental than the one in common use and gives a more symmetrical finish to the hub.

What I claim as my invention and desire to secure by Letters Patent, is

The curved form or ornamental configuration of carriage hub sand bands herein described and represented in the annexed drawing.
